ATTORNEY

UNITED STATES PATENT OFFICE.

GEORGES AUCOC, OF PARIS, FRANCE.

METALLIC WEB OR FABRIC.

No. 898,166.

Specification of Letters Patent. Patented Sept. 8, 1908.

Application filed March 26, 1908. Serial No. 423,422.

To all whom it may concern:

Be it known that I, GEORGES Aucoc, citizen of the French Republic, residing at Paris, France, have invented certain new and useful Improvements in Metallic Webs or Fabrics, of which the following is a specification.

The present invention relates to a metallic web or fabric for the manufacture of purses, bags, bracelets, collars and similar articles of a more or less ornamental nature.

In its simplest form the invention includes a plurality of rings or annular members interconnected by a central connecting member.

Several forms of the invention are illustrated in the accompanying drawing, wherein

Figure 1 is a perspective view of a fragment of metallic webbing constructed according to my invention; Fig. 2 is a similar view of a connecting member; Fig. 3 is an elevational view of a purse embodying my invention. Fig. 4 is a similar view of a chatelaine; and Figs. 5 to 8 are schematic views illustrative of various forms which the invention may take.

In constructing my improved web I employ a plurality of rings *c* each of which may have secured thereto as by radial arms *d* a central preferably inset portion or stud *a* which is preferably provided with a setting *b* in its head for the reception of precious or semi precious stones.

The rings above described may be connected by the connecting member to be hereinafter described in groups of two, three, four or such other number as may be desired, and stones of different kinds may be placed in the settings to attain the required ornamental effect.

The connecting member which I employ is best seen in Fig. 2, wherein *f* designates a central shank, preferably having a head *e* which may be provided with a setting *h* wherein stones may be set. The shank *f*

carries a plurality of ears *g* which are designed to pass through the rings *c* thus inter- 45 connecting any desired number of the latter, the number of rings in each group being dependent upon the number of ears of its connecting member.

While in Fig. 2 the central connecting 50 member is shown as having four ears *g*, it will be noted upon reference to Fig. 5 that it is feasible to provide the member with two such ears, or as shown in Fig. 6 three ears *g* 55 may be used, the number of ears of each connecting member being optional.

In Fig. 8 I have illustrated a construction wherein four rings *c* are centrally united by a connecting member having four ears and in addition the rings are also held together in 60 pairs by links *i* passing therethrough.

It is to be understood that my invention is not limited to any particular form of ring or connecting member, nor to any particular number of rings forming individual groups, 65 but

What I claim as new and desire to secure by Letters Patent is:—

As a new article of manufacture, a metallic web or fabric for the purposes specified, comprising a plurality of rings connected in groups, each ring having a central inset portion provided with a setting for the reception of ornamental stones, and each group of rings being centrally connected by a member 70 comprising a stud *f* having a head *e* and a setting *h* therein, and the rings of said groups being connected in pairs by links *i*, substantially as described.

In testimony whereof I have affixed my 80 signature in presence of two witnesses.

GEORGES AUCOC.
